UNITED STATES PATENT OFFICE.

HORACE D. SHERRILL, OF NEW YORK, N. Y.

DESIGN FOR A FINGER-RING.

SPECIFICATION forming part of Design No. 18,840, dated April 3, 1883.

Application filed November 1, 1882. Term of patent 3½ years.

To all whom it may concern:

Be it known that I, HORACE D. SHERRILL, a citizen of the United States, residing in the city, county, and State of New York, have invented and produced a new and original Design for Finger-Rings, of which the following is a full, clear, and exact description.

Reference is to be had to the accompanying drawings, forming part of this specification, in which similar letters of reference indicate corresponding parts in both the figures.

Figure 1 is a front view of my newly-designed finger-ring, and Fig. 2 is an end view of the same.

15 The feature of my design consists in a gold letter or monogram, A, provided with a number of diamonds, B, or other precious stones, which monogram is secured on a curved stone, C, within the setting of a finger ring. The 20 said stone C is curved in the same direction as the circle of the ring.

The letter may be made of any desired style or shape, and may be ornamented, more or less, with precious stones, and the stone C, on which 25 the letter is secured, may have any desired color; but preferably I use a jet-black stone—for instance, onyx—upon which a gold letter with diamonds is secured.

The shanks of the ring may be made or ornamented in any desired manner or style, as I 30 do not wish to limit myself to the style shown.

The monogram may be made of any desired size, and may be provided with more or less precious stones.

Instead of making the monogram of gold, it 35 may be made of silver or platinum, if desired.

I am aware that it is not new to use a monogram on the flat surface of a ring-stone, or to inlay the metal in white and gold colors, or to inlay the panel with diamonds or other stones, 40 to represent eggs; but

What I do claim is—

A design for the setting of a finger-ring, which consists of a curved stone or ground, a monogram of different color from the stone and 45 mounted thereon, and bright stones or diamonds arranged on the outer surface of the monogram, all together presenting the appearance and aspect shown and described.

HORACE D. SHERRILL.
